DESIGN FOR A HOBBYHORSE

Robert C. Swengel, York, Pa.

Application November 12, 1946, Serial No. 134,702

Term of patent 14 years

(Cl. D34—15)

To all whom it may concern:

Be it known that I, Robert C. Swengel, a citizen of the United States, residing at York, in the county of York and State of Pennsylvania, have invented a new, original, and ornamental Design for Hobbyhorses, of which the following is a specification, reference being had to the accompanying drawing, forming part thereof.

Figure 1 is a side elevation of a hobbyhorse, showing my new design.

Figure 2 is a plan view thereof, and

Figure 3 is an end elevation thereof.

The essential features of my invention are shown by the full lines on the drawing.

I claim:

The ornamental design for a hobbyhorse, as shown and described.

ROBERT C. SWENGEL.
